NEEDLE CARRIER

Bernard N. Pierce, Avon, Conn., assignor to The
Merrow Machine Company, Hartford, Conn.,
a corporation of Connecticut

Application January 30, 1950, Serial No. 141,318

10 Claims. (Cl. 112—162)

1

In certain overseaming machines a curved eye-pointed needle is oscillated to follow an arcuate path extending above and below a needle plate for cooperation with looper elements in the formation of overedge stitches. Sewing machines of this type are operated at high rates of speed and it is important that bearing surfaces of the needle carrier and a stud for pivotally supporting the carrier be kept lubricated continuously with a film of oil therebetween. During operation of such a machine a slight flow of oil is diverted from the indicated bearing surfaces as from the effect of vibration and centrifugal force and this diverted oil is prone to accumulate on the outer face and adjacent areas of the needle carrier in sufficient quantity to be finally cast therefrom and onto the work as the latter is fed over the work support and needle plate therebelow. For obvious reasons this oil thrown onto the work is objectionable.

To prevent discharge of oil from a needle carrier onto the work is the object of the present invention. With this end in view an important feature of the invention consists of a particular formation of the needle carrier with relation to the needle carrier supporting stud which is effective to so divert oil from the carrier that it will be disposed of harmlessly. The form and arrangement of parts for attaining this purpose is fully set forth in the following detailed description, illustrated in the accompanying drawings and defined in the appended claims.

In the drawings—

Figure 1 is an end view of an overseaming machine having an oscillatory needle carrier and a needle carrier stud appropriate for inclusion therewith of means comprising this invention.

Figure 2 is a detail view of the needle carrier and associated parts in the sewing machine illustrated in Fig. 1, with the needle at one end of its range of movement.

Figure 3 is a view similar to Fig. 2 but with the needle at the opposite end of its range of movement.

Figure 4 is a sectional view on line 4—4 of Fig. 3, also showing parts related to those of Fig. 3.

Figure 5 is a sectional view on line 5—5 of Fig. 4.

Referring to the drawings the overseaming machine illustrated thereby is of the well known "Merrow" type in which the stitch forming implements comprise a curved eye-pointed needle 1, an upper looper 2, and a lower looper 3. Mechanism for actuating these implements is not here

shown but is fully disclosed in numerous patents, as for example, in United States Letters Patent No. 1,983,631, granted December 11, 1934, upon application of Joseph M. Merrow.

5 To support the needle 1 for oscillatory movement it is mounted in a carrier 4 having a hub 5 (Fig. 4) and a web portion 6 at the outer end of the hub, the latter being provided with a tapered bearing hole 7. Web 6 merges into an arm 8 from which on the hub side of the web, a stud 9 extends and at a free extremity of the web a head 10 extends oppositely somewhat beyond the plane of the outer web surface 11. Head 10 is provided with a stud 12 to receive thereon a washer 13, which to prevent its turning with respect to the head 10 is keyed to the latter as at 14. A nut 15 threaded on stud 12 serves to urge clamp or washer 13 toward head 10 to secure therebetween the needle shank 16 which passes 10 through a hole in stud 12. For a purpose that will presently be described, a channel or duct 17 is formed in the outer face 11 of carrier 4 and intersects the wall of tapered hole 7 and the peripheral surface of web 6 in proximity to where the latter projects as a rib 18 only slightly beyond the similar surface of hub 5. The stud 9 before mentioned and extended from relatively short arm 8 of the needle carrier, receives a link connection 19 which is associated with carrier actuating means hereinafter described.

Serving to pivotally support the carrier 4, is a screw threaded stud 20 having a slotted head 21 which is longitudinally tapered to correspond to the taper of hole 7 in said carrier. With the wall 35 of hole 7 engaged by stud 20, the latter may be screwed into machine frame 22 until the inner end surface of hub 5 is brought into engagement with frame surface 23 to thereby establish bearing fit between respective tapered surfaces of the 40 stud and the carrier. This adjustment when completed may be secured in desired precise relation by set screw 24 (see Fig. 5). The bearing surface of head 21 of stud 20 is of a length that is shorter than hole 7 for the purpose of leaving 45 within the outer end of hole 7, a space or recess 25, from which, channel or duct 17 forms an exit through which oil exuded from between the bearing surfaces may escape and be harmlessly disposed of as will presently appear.

50 Means for actuating the needle carrier 4 include a driven shaft 26 having a head 27 journaled in machine frame 22. A stud 28 eccentrically disposed on head 27 is engaged by link 19, above mentioned as engaged at its opposite end 55 with stud 9 on carrier 4. Thus, rotation of shaft

26 moves link 19 so that the needle carrier is oscillated about its pivotal axis to move the needle in the arcuate path which it travels in making successive penetrations of the work as W supported on needle plate 29 and work support 30 (see Fig. 4). Extreme positions of the needle carrier in its range of movement in this arcuate path are shown respectively in Figs. 2 and 3.

For lubricating the several bearing surfaces indicated in the above description, oil may be applied in hole 31 (see Fig. 4). From this source oil traversing the bearing of shaft head 27 and passing through a channel 32 in face 23 of machine frame 22 is delivered to the bearing surface between carrier 4 and its supporting stud 20 whence it passes outwardly into the recess 25 provided at the end of the bearing surface of the stud 20. Oil in this recess under the effect of gravity tends to flow downwardly toward channel or duct 17. This oil is also acted upon by centrifugal force created by movement of carrier 4, and is therefore expelled through channel 17, or in other words, diverted from moving out onto the outer lateral face of said carrier where it is objectionable for the reason already stated. The oil thus expelled through channel 17 may not be entirely cast from the carrier. Whatever small amount remains thereon, however, tends to move onto and along the perimeter of web 6 and not onto the outer web surface 11 where it is particularly objectionable. To advantageously dispose of the trace of oil reaching the perimeter of web 6 at the base of arm 8, it is directed to the outer extremity of said arm at the base of stud 9 and thence onto said stud to lubricate engagement therewith of link 19. To facilitate such passage of oil, the outer edge of arm 8 is beveled as at 33. That is, an inclined surface is formed at the base of stud 9, and as shown, extends toward the base of the arm into proximity with channel 17.

Thus the needle carrier and parts associated therewith may be defined briefly as comprising, a support, a pivotal stud carried thereby, an element mounted on the stud, said element including a hub and web portion, with the hub somewhat longer than the bearing surface of said stud engaged thereby so that a recess is provided in the outer face of the hub adjacent to the end of the bearing hole for the stud, said web around a portion of the hub circumference forming a slight rib and therebeyond merging into an arm having a needle-holding head, and also merging into an actuating arm for suitable engagement with means for operating the carrier, and the web being formed with a channel or duct intersecting the recess and leading outwardly therefrom to the perimeter of the rib or web.

It will be understood that the present invention is not limited to the exact details herein shown and described and that the principles involved may be applied in other mechanisms without departure from the scope and spirit of the invention as defined by the appended claims.

Having thus described my invention, what I claim is:

1. In a sewing machine, a support, an element having a hole therethrough and a duct extended from the exterior of the element into said hole, and a stud having bearing engagement within the hole to pivotally secure the element to the support, the outer end of the bearing surface of said stud terminating short of the duct.

2. In a sewing machine, a support, an element having a hub and a web portion merging with the

hub, a stud having bearing engagement within a hole in the hub to pivotally secure the element to the support with an end of the hub remote from the web adjacent to the support, and means for diverting oil from adjacent the outer end of the bearing surface of said stud outwardly through the web.

3. In a sewing machine, a support, a needle carrier, a tapered pivotal stud for engagement with a correspondingly tapered hole in the needle carrier whereby the carrier is supported for oscillation on the stud with a side of the needle carrier held against the support, the bearing surface of said stud terminating within the hole to provide a recess in the outer face of the carrier, and means for diverting oil from said recess outwardly through the carrier.

4. In a sewing machine, a support, a needle carrier, and a pivotal stud, said needle carrier comprising a hub and a web portion, said pivotal stud being tapered for engagement with a correspondingly tapered hole in said hub whereby the carrier is supported for oscillation on the stud with an end surface of the hub held against the support, the bearing surface of said stud terminating within the hole to provide a recess adjacent the outer face of the carrier, said carrier having a duct therein leading from the recess to the perimeter of the needle carrier web.

5. In a sewing machine, a support, a needle carrier, and a pivotal stud, said needle carrier comprising a hub and a web with the web portion forming a needle carrying arm, an arm whereby the needle carrier is actuated, and a rib on the hub, said pivotal stud being tapered for engagement with a correspondingly tapered hole in said hub whereby the carrier is supported for oscillation on the stud with an end of the hub held against the support, the bearing surface of said stud terminating within the hole to provide a recess adjacent the outer face of the carrier, said carrier having a duct therein leading from the recess to the perimeter of the arm whereby the carrier is actuated.

6. In a sewing machine, a support, a needle carrier, and a pivotal stud, said needle carrier comprising a hub and a web merged therewith, the latter including an arm whereby the needle carrier is actuated, said pivotal stud being tapered for engagement with a correspondingly tapered hole in said hub whereby the carrier is supported for oscillation on the stud with an end of the hub held against the support, the bearing surface of said stud terminating within the hole to provide a recess adjacent the outer face of the carrier, said carrier having a duct therein leading from the recess to the perimeter of said arm.

7. In a sewing machine, a support, a stud projecting outwardly from said support and having an inwardly tapered bearing surface, and a needle carrier having a hub and a web portion extending from said hub, said hub being formed with a hole having an inwardly tapered wall surrounding said tapered bearing surface pivotally mounting said carrier on said support, the wall of said hole extending outwardly from said support beyond the bearing surface of said stud to provide a recess at the outer face of said hub, said carrier being formed with a duct extending from said recess to the edge of said carrier.

8. In a sewing machine, a support, a stud projecting outwardly from said support, and a needle carrier having a hub and a web portion extending from said hub, said hub being formed with a hole having a bearing fit on said stud

pivotsly mounting said carrier on said support, said hub extending outwardly from said support beyond the outer end of said stud to provide a recess at the outer face of said hub, said carrier being formed with a duct extending from said recess to the edge of the carrier.

9. In a sewing machine, a needle carrier comprising a web, a hub at one side of said web, said hub having a hole therethrough, the inner portion of the wall of said hole forming a bearing surface for pivotsly mounting the carrier on a support, the outer portion of the wall of said hole constituting a recess for collecting lubricant discharged from the bearing surface, a needle carrier head at the other side of said web, and an operating arm extending from said web adjacent said hub, said other side of said web being formed with a duct leading from said hole and to the edge of said web between said hub and said operating arm, said duct communicating with said 20 recess for conducting lubricant therefrom.

10

10. In a sewing machine, a needle carrier comprising a web, a hub at one side of said web having a hole therethrough, a needle carrier head at the other side of said web, and an operating arm extending from said web adjacent said hub, said arm having an inclined surface merging with the edge of said web, said web being formed with a duct leading from said hole to the edge of said web adjacent said inclined surface.
